UNITED STATES PATENT OFFICE

2,510,924

CARD FILING EQUIPMENT

George C. Bruen, deceased, late of Chicago, Ill., by
Sophie E. Bruen, executrix, Chicago, Ill.

Application August 28, 1946, Serial No. 693,455

8 Claims. (CL 45—3)

1

This invention relates to card filing equipment and more especially to rotary card indexes of the kind in which the cards are detachably connected to the periphery of a mounting drum or wheel having a horizontal axis of rotation.

One of the major novel features of this invention resides in a structure adapted to fabrication largely from sheet metal by relatively inexpensive processes and including the combination of a rotatable mounting drum and a plurality of card-holding trays which are quickly attachable to and detachable from the mounting drum and which, when detached, are adapted to rest on a flat horizontal surface such as a desk top, so that the cards carried thereby can conveniently be examined.

It previously has been proposed—see, for example, United States Patent No. 2,168,323 of August 8, 1939, and United States Patent No. 2,240,325 of April 29, 1941, both issued to George C. Bruen—to provide a card-holding tray adapted to rest on a desk and to receive and support a section of card track, with the cards thereon; but in those instances the card-holding tray does not form a part of the mounting drum or rotary index but is, instead, a separate and distinct entity which either takes up desk space when not actually in use or must be stowed in some available place, which may not always be conveniently accessible. And, where it may be necessary to have several card track sections detached from the drum simultaneously, it is necessary to provide enough trays or adapters to accommodate the probable maximum number of detached trays. The present invention avoids the necessity of providing storage space for an auxiliary tray or trays or similar supports, by incorporating such supports as removable units in the structure of the rotary index itself. Thus, whenever a section or group of cards is removed from the index wheel, the tray or other support comes with it, and the user is enabled immediately to set the detached group of cards on his desk in complete readiness for inspection.

Another feature of this invention resides in a novel and highly economical construction of the mounting drum which, in order to accommodate the detachable card trays, is made preferably of polygonal form, having a plurality of flat, tangential peripheral surfaces conforming to the flat bottom surfaces of the several trays, and each of a size to accommodate one tray, individually.

Still another feature of the invention has to do with a novel provision for connecting the several card trays to the periphery of the mounting

2

drum in such manner that they are quickly and easily detachable individually.

According to one embodiment of the invention the cards are mounted on the index wheel or drum in sectional rows extending peripherally thereof and forming a continuous series encircling the drum, whereas in another embodiment each card-carrying tray supports its cards in a row extending transversely of the drum; and in the latter case the card trays are slidably mounted so that each tray, with its respective cards, can be withdrawn from the drum laterally. This also constitutes one of the novel features of the invention.

15 The principal objects of this invention will be apparent from the above enumeration of novel features. Additional objects and novel features will be brought out as incidents to the detailed description hereinafter.

20 In the four sheets of drawings which accompany this specification:

Fig. 1 is a side elevational view of a rotary card index according to one of the preferred embodiments of the invention;

25 Fig. 2 is a vertical transverse section taken at line 2—2 of Fig. 1;

Fig. 3 is an enlarged sectional view taken at line 3—3 of Fig. 2, showing a constructional detail;

30 Fig. 4 illustrates a card suitable for use with the subject rotary index;

Fig. 5 is an enlarged fragmentary view, partly in section and partly in elevation, showing details of construction of the mounting drum and illustrating the manner of attaching and detaching the card trays to and from the periphery of the drum;

35 Fig. 6 is a fragmentary plan view taken at line 6—6 of Fig. 5;

Fig. 7 is a sectional view taken at line 7—7 of Fig. 5; and

40 Figs. 8, 9 and 10 illustrate an alternative embodiment of the invention; Fig. 8 being a sectional view taken at line 8—8 of Fig. 10; Fig. 9 a plan view looking at the periphery of the drum, with one of the card trays removed; and Fig. 10 a sectional view taken axiswise of the drum and showing details of the card tray and the spring clip for yieldably retaining the same in normal position on the drum.

45 That embodiment of the invention which is shown in Figs. 1 to 8, inclusive, comprises a sheet metal housing 10 made principally of steel plates welded together and provided with four sheet metal supporting legs 11. The housing is open

at the top, between points 12 and 13, to provide access to the cards therein; but it may be closed when not in use by an arcuate sheet metal hood 14 which is mounted for rotation about the axial center of the housing and provided with an outwardly extending flange or lip 14a which serves both to limit the movement of the hood, in both directions, and to afford a finger hold for operating the hood.

Welded or otherwise secured to the respective interior surfaces of the two side walls of housing 10 are a pair of oppositely disposed bearing blocks 15 and 16 which provide bearings for both the hood 14 and an index wheel or drum which is designated as a whole by reference numeral 17.

The index wheel includes a cross shaft 18, journaled at its ends in the bearing blocks 15 and 16, which are bored axially to afford bearings for the shaft and slotted radially, as indicated at 19 and 20 (Figs. 1, 2 and 3), to permit the index wheel to be lifted bodily from its bearings and from the housing.

A cylindrical hub 21 is fixedly secured to shaft 18 and is rotatable therewith. Said hub spans the space between the opposing faces of bearing blocks 15 and 16, and thus serves to locate index wheel 17 axially between the housing walls.

Attached to and extending radially from hub 21 are four spokes 22 of a hand wheel 23 having an annular tubular rim 24 which is welded to the outer ends of said spokes. Hand wheel 23 serves to facilitate manual rotation of the index wheel.

As depicted most clearly in Figs. 2 and 5, hub 21 has eight peripheral slots 25 equally spaced circumferentially and each adapted to receive a wedge block 26 and the inner edge portion of a sheet metal radially extending spoke 27a forming one leg of a generally V-shaped sheet metal element 27 which includes a peripheral rim portion 27b and an inwardly directed radial flange 27c. Each wedge block 26 is secured to hub 21 by means such as a pair of capscrews 28 which are threaded into the hub; and each serves firmly to clamp to the hub the immediately adjacent spoke 27a.

Each inwardly directed flange 27c is welded or otherwise secured to the spoke portion 27a of the next adjacent V-shaped element 27; and, as will be apparent, the several elements 27 constitute sectors forming, conjointly, a polygonal sheet metal wheel structure which completely encompasses the hub and, in the disclosed embodiment, has eight flat peripheral surfaces constituting the sides of an octagon.

The hub 21 and shaft 18, together with the structure composed of the sheet metal elements 27, constitute what is herein referred to as a mounting drum, on the periphery of which are detachably mounted a number of card-holding trays 29 equal to the number of flat surfaces on the drum. Each tray 29 is composed of a sheet metal member 30 having a bottom plate 30a, two side walls 30b and 30c, a high end wall 30d and a low end wall 30e. As viewed in Fig. 7, the cross section of each tray has the form of a channel; and the upper edges of the side walls 30b and 30c are each curved in concentric relationship to the axis of the mounting drum. Welded or otherwise secured to the arcuate upper edge of each side wall 30b, 30c is a bar 31 of round cross section. Each of said bars extends from the high wall 30d to a point 32 somewhat beyond the front edge of the tray, as shown in Fig. 5. The overhanging end 32 of each bar 31 is slotted, as shown

in Fig. 6, to receive a flange 33 forming an integral part of the high end wall 30d of the next adjacent card tray. This serves to avoid the presence of a gap between the ends of the card-carrying bars of one tray and the high end wall of the next tray, through which gap cards might become unintentionally detached; and it also aids in lining up the trays on the drum.

Each bar 31 with its supporting side wall 30b or 30c forms a card track, the pair of which are spaced laterally in correspondence with the spacing of two keyhole shaped notches 34 in the lower edge of each card 35, an exemplary embodiment of which is shown in Fig. 4. The cards are attached to the tracks by notches 34, and each tray is capable of accommodating a large number of cards. Groups of cards may be threaded onto the tracks at the front end thereof, the end wall 30e being low enough to afford no obstruction, and they may be withdrawn from the same end of the track when the tray is lifted at the front end, as shown in dot and dash lines in Fig. 5, or is removed from the drum. Individual cards or small numbers thereof may, however, be withdrawn or placed upon the tracks, without moving the trays, by force applied to the cards which distorts the lower portions of cards adjacent the slots. The rear end wall 30d is high enough to form a backstop for the cards, thus enabling the tray to be lifted at its front end and removed from the drum without any of the cards becoming detached.

Extending outwardly in a radial direction from each rim portion 27b, and integral therewith, are a pair of laterally spaced lugs 36, to each of which is rigidly secured a pin 37. Lugs 36 are spaced axially of the drum an amount sufficient to receive between them the rear end of a tray; and the two side walls 30b and 30c are each notched at 38 (see Fig. 5) to engage said pins 37. Pins 37 serve to anchor and locate the back ends of their respective trays, while the front end of each tray is detachably secured to the drum by a pair of latch members 39, 40 which are pivotally mounted on a shaft 41, the two ends of which are journaled in a pair of lugs 42 which are integral with their respectively associated rim portions 27b and project inwardly in a radial direction therefrom. The two latch members 39 and 40 project through apertures 43 in the rim portion and through registering apertures 44 in the bottom plate 30a of the card tray. The hook ends of the latches overlie and bear down upon the bottom plate of the card tray, as shown in Fig. 5, and thus serve to hold down the front end of the tray. Each latch member 39, 40, or at least one of them, has an integral tail piece 39a, 40a which, preferably, is curved arcuately about the axis of shaft 41 and projects through aligned openings 45, 46 in rim portion 27b and bottom plate 30a, respectively. Said tail pieces, or either of them, may be manually depressed to rotate the latch members, thus releasing the associated card tray and permitting its withdrawal from the drum.

The two latch members of each pair are connected by a cross strip 47 which may be integrally formed with one or both latch members. This connection causes the two latch members to rotate together, thereby making it unnecessary to depress both tail pieces manually at one time to remove a tray. The operator thus has one hand free to lift the front end of the released card tray, while the other is used to depress one of the tail pieces. The two latch members of

each pair are spring biased, counterclockwise, as viewed in Fig. 5, by a leaf spring 48 which partially encircles shaft 41 in contact therewith, and bears at one end against the under side of cross bar 41, the other end bearing against the adjacent spoke 27a.

Each tray 29 with the cards thereon can be removed bodily from the drum upon releasing the latch and can easily be restored to the drum when no longer needed for reference. When removed from the drum, each tray is adapted, by reason of its smooth, flat bottom, to rest on the top of a desk or other convenient flat supporting surface, thus enabling the user to examine the cards in comfort and without requiring the use of a special adapter for the card tracks.

In the alternative structure of Figs. 8 to 10, inclusive, the mounting drum construction is substantially identical with that illustrated in Figs. 1 to 7, inclusive, and previously described, except as hereinafter pointed out.

Instead of the hand wheel 23, there is substituted in the structure of Figs. 8 to 10 a series of bail-like handles 49, each comprising a bent rod having two legs 59 and 59a, welded at their two ends to opposite edges of a spoke 27a, and a cross member 59b having a tubular rubber covering 51 which serves as a grip. The index wheel is rotatable by manual force applied to handles 49.

Punched out of each rim portion 27b are four ears 52 which are bent to form, conjointly, a pair of guides in which are slidably mounted a card tray 53. Each tray is slideable in its guides axially of the drum, as clearly indicated in Fig. 10; and the row of cards 54 extends transversely of the drum and longitudinally of the tray.

Each rim portion 27b of the alternative structure has an upturned extension 55 integral therewith which serves as a backstop for the cards on a tray 53. The latter can be withdrawn from the drum at one side only, as indicated by the dot and dash outline in Fig. 10, whereina tray is depicted as partially withdrawn.

Each card tray 53 comprises a bottom plate 56, two spaced side walls 57, 58, a high front wall 59, and a low back wall 60, all of which are one piece of sheet metal, which is bent at the junctions of the bottom plate and side walls to form outwardly extending opposite flanges 61, 62 which are slidably engaged by ears 52. Two round bars 63, 64 are fixedly attached to the upper edge portions of side walls 57, 58; and these, together with the side walls, constitute a pair of tracks on which the cards 54 are mounted. Cards 54 may be identical with cards 35 shown in Fig. 4.

For the purpose of yieldably retaining the card tray in its normal position on the drum, there is attached to each rim portion 27b a leaf spring 65 having a detent portion 66 which projects through an aperture in said rim portion and engages a registering aperture in bottom plate 56 of the tray.

When the card tray is withdrawn, either partially or fully, the back end of the track is unobstructed and cards can consequently be withdrawn in groups from the track or applied thereto, but the track will hold the cards in nearly upright posture, as shown in Fig. 10, without any additional rear support. Thus the tray can be wholly withdrawn from the drum and placed on a desk top for reference without any likelihood of cards becoming detached from the track. Individual cards may be separately removed from the track without removal of a tray.

Two specific embodiments of the invention have been shown and described by way of example, but it will be understood that the scope of the invention is not to be regarded as limited except as indicated by the terms of the appended claims.

Having thus described the invention, what is claimed as new and desired to be secured by Letters Patent of the United States, is:

1. Card filing equipment comprising a rotatable drum having a horizontal axis of rotation, said drum having a continuous series of flat peripheral surfaces forming a polygon, a plurality of card-holding trays mounted individually on said peripheral drum surfaces and detachably secured thereto, each of said trays comprising a bottom plate, an end wall and two laterally spaced side walls extending normally to the bottom plate and to said axis, and a pair of bars each secured to the free edge of one of said side walls and forming therewith a card-holding track, a pair of tray anchoring pins carried by said drum for each of said trays individually, each tray being notched at one end to engage its associated anchoring pins for detachably securing that end of the tray to the drum, and a plurality of spring latches carried by the drum, one for each tray, each spring latch being adapted to releasably engage the other end of its associated tray, said anchoring pins and latches being operative, conjointly, detachably to secure their respective trays to the drum.

2. In a rotary index, a drum comprising a hub having a plurality of peripheral slots spaced circumferentially and extending axially thereof, and a framework carried by said hub and encircling the same and having a polygonal periphery concentric with the hub, said framework comprising a plurality of V-shaped and integral sheet metal elements each comprising two major flat portions, one of the major flat portions of each said element forming one side of said polygonal periphery while the other major flat portion forms a spoke extending radially from the hub and having one edge inserted in one of said slots, individually, and anchored therein, said V-shaped elements being connected together to form an articulated structure, and a plurality of card-holding trays detachably connected to the periphery of said drum and rotatable therewith.

3. In a rotary index, a sheet metal housing having an opening at the top for access to the interior thereof, a pair of bearing blocks carried by said housing interiorly thereof and spaced apart, a shaft journaled at its two ends in said blocks, a hub mounted on said shaft between said blocks and rotatable therewith, a drum including said hub and a sheet metal framework mounted on and encircling the hub, said drum having a polygonal rim, said framework comprising a plurality of identical sheet metal elements, each of said elements comprising a spoke portion and a rim portion, one end of each spoke portion being connected to said hub, said rim portions being secured together end to end, a plurality of card-holding trays adapted to be attached, individually, to said rim portions and supported thereby, each of said trays comprising a flat bottom plate seated on its supporting rim portion, exteriorly thereof, a pair of spaced side walls integral with the bottom plate, and a pair of bars secured respectively to the outer edges of said side walls and extending parallel thereto peripherally of the drum, a pair of anchoring pins for each of said rim portions and carried thereby,

each of said trays being notched at one end for anchoring engagement by its associated anchoring pins, and a plurality of latches, one for each said rim portion, each of said latches being pivotally supported at the inner side of its associated rim portion, each latch comprising a hook portion and a tail piece, said hook portion extending through an opening in the rim portion and an opening in the bottom plate of the tray and adapted to latchingly engage said bottom plate for securing the tray to the drum in cooperation with said anchoring pins, said tail piece extending through an opening in the rim portion and through an opening in said bottom plate to the interior of the tray, spring means biasing said latch toward latching position, said latch being releasable by manually depressing said tail piece.

4. Card filing equipment comprising a drum having a horizontal axis of rotation, said drum having a sheet metal rim, a pair of laterally spaced lugs attached to said rim and projecting outwardly therefrom in a radial direction, a pair of anchoring pins each carried by one of said lugs individually and having a common axis which is parallel to the axis of rotation of the drum, a second pair of laterally spaced lugs attached to said rim and projecting inwardly therefrom toward the axis of the drum, said first and second pairs of lugs being spaced apart peripherally of the drum, a shaft carried by said second pair of lugs interiorly of said rim and extending parallel to said axis of rotation, a pair of latch members pivotally mounted on said shaft and spaced apart lengthwise thereof, said latch members each comprising a hook portion extending through an opening in said rim and projecting outwardly from said rim, means joining said latch members to effect unified rotation thereof, spring means biasing said latch members toward latched position, and a card-holding tray having a bottom plate resting on said rim, said tray being notched at one end to engage said anchoring pins whereby to anchor that end of the tray to the rim, said bottom plate having openings through which said hook portions extend, said hook portions latchingly engaging said bottom plate and functioning to releasably secure said tray to the rim at the end thereof remote from said anchoring pins.

5. Card filing equipment comprising a drum having a horizontal axis of rotation, said drum comprising an axial hub having a plurality of peripheral slots extending lengthwise thereof and spaced circumferentially, a plurality of identical sectors conjointly encircling said hub, each of said sectors consisting of a sheet metal element comprising a spoke portion and a rim portion, one end of each spoke portion being inserted in one of said slots, a plurality of wedge blocks disposed individually in said slots and operative to anchor the spoke portion therein to said hub, said rim portions having end flanges thereon for joining adjacent rim portions in series to form a substantially continuous rim encircling said hub and concentric therewith, each of said rim portions being flat, thereby rendering the rim of the drum polygonal in form as viewed edge-wise.

6. Card filing equipment comprising a drum

having a horizontal axis of rotation, said drum comprising an axial hub and a plurality of sectors conjointly encircling said hub, each of said sectors consisting of a sheet metal element comprising a spoke member and a rim member, one end of said spoke member being connected to said hub and the other end to one end of the rim member, said rim members being joined in series to form a rim completely encircling said hub and concentric therewith, and a plurality of U-shaped handles projecting radially from said drum, each handle comprising a pair of legs and a cross member interconnecting said legs, said legs being connected to opposite edges, respectively, of one of said spoke members.

7. Card filing equipment comprising a rotatable drum including integrally formed spokes and peripheral sections each made of a single sheet of metal having parallel ends and opposed side edge portions including parallel and angularly disposed parts, said peripheral sections being secured together, each of said sheets of metal also being formed at the parallel ends thereof to provide attaching portions, a plurality of card-holding trays, each of which is capable of supporting itself in upright position on a desk top and including means for holding a plurality of cards in a row, and means for releasably securing said trays individually to the periphery of said drum, whereby said trays can be individually removed from and attached to said drum.

8. Card filing equipment comprising a rotatable drum having a horizontal axis of rotation and a supporting structure made of similar integrally formed sheet metal sections secured together, each of said integral sections including a spoke portion having thereon a hub flange and a flat peripheral portion having a flange for abutment with an adjacent section, a plurality of card-holding trays carried by said drum at the periphery thereof and disposed thereabout in concentric relationship to said axis, each of said trays comprising a card-holding track and a bottom plate by which it is attached to the drum, said bottom plate being adapted to serve as a base for supporting said track and the cards thereon in an upright position when the tray is removed from the drum and placed on a desk top or other horizontal supporting surface, and latch means for detachably holding each tray in position on one of the flat peripheral sections of the drum.

SOPHIE E. BRUEN,
*Executrix of the Last Will and Testament of
George C. Bruen, Deceased.*
